UNITED STATES PATENT OFFICE.

GEREONOUS L. WILSON, OF CHICAGO, ILLINOIS.

RAILWAY-SIGNAL.

SPECIFICATION forming part of Letters Patent No. 712,430, dated October 28, 1902.

Application filed September 16, 1901. Serial No. 75,633. (No model.)

To all whom it may concern:

Be it known that I, GENEOROUS L. WILSON, a citizen of the United States, residing at Chicago, in the county of Cook and State of Illinois, have invented a certain new and useful Improvement in Railway-Signals, of which the following is a specification.

Railway accidents in many cases result from the washing away of a bridge over a cut, stream, or culvert and from the lodgment on the track of rocks and debris from an embankment.

The object of this invention is to provide a preventive against accidents from the sources named by employing a signal which is operated from the washing away of the bridge or from debris on the track and have such signal positively actuated so as to warn an approaching train of the condition of the track; and the invention consists in the features of construction and combination of parts hereinafter described and claimed.

In the drawings illustrating the invention its application to a bridge and to an embankment is shown.

Figure 1 is a side elevation of a section of a railroad, showing a bridge over a river or cut with the invention in connection therewith; Fig. 2, a top or plan view of the arrangement of Fig. 1; Fig. 3, a side elevation of a signal-post, showing the signal closed; Fig. 4, a similar view to Fig. 3, showing the signal open; Fig. 5, a sectional plan or edge view of the signal arm or support and the signal; Fig. 6, a face view or side elevation of the signal arm and signal with the slide of the arm drawn away to expose the signal; Fig. 7, an outline view showing a signal arrangement for a station in connection with an alarm-bell.

The invention is applicable to bridges over rivers, creeks, or cuts generally and to culverts or other places where there is a depression beneath the track supported on a trestle or bridgework.

The application of the invention to a bridge or trestle or other similar structure is shown in Figs. 1 and 2. The track A and road way or bed B are of the usual construction and formation for such parts of a railway, and the bridge or trestle C can be of the usual construction over a cut or bed C', and these parts therefore are not specifically described. At

one side of the track and extending over the bridge or trestle and on each end of the bridge or trestle alongside the rails is a wire cable, 55 rod, chain, or other suitable device which can be securely attached and fixed to the stringers or cross-ties of the bridge, trestle, or other structure and be permanent therewith and constitute a means for operating a signal in 60 case the bridge, trestle, or other structure is washed away or broken down. The attachment of the wire, cable, rod, chain, or other device to the bridge, trestle, or other structure in the construction shown in Figs. 1 and 2 65 is to the cross-ties and is by means of suitable staples or spikes b or in any other suitable manner. The signal-operating means after leaving the bridge, trestle, or other structure at each end is preferably inclosed within 70 a tube or casing c, attached to the cross-ties or otherwise held in position and extending on each side to a signal-station or to a regular station of the road, with the signal-operating means likewise extending therein. At each 75 end of the bridge, and at a distance therefrom not to be affected by the washing away or falling of the bridge, and at a distance to enable a train to be stopped, is located a hollow post or upright D, into which a wire or other connection leads from the signal-operating means attached to the bridge, trestle, or other structure, and, as shown, the connection d runs through a tube or casing c' branching out from the tube or casing c, and to facilitate ease of 80 movement for the connection it can be guided and run over pulley or guide wheels d' or other suitable guides located at the top and bottom of the post. The upper end of the post has extending out therefrom an arm E, provided on 85 its top and bottom edges with a guide e, between which is a sliding cover or plate E', to which at one end is attached the end of the wire or other connection d, and, as shown, a coil d' is provided at the point of attachment to the 90 sliding cover or plate, which coil permits of expansion and contraction of the wire or other connection without moving the sliding plate or cover sufficiently far to disclose the signal. Each arm E carries a suitable signal, which 95 can be observed from an approaching locomotive or train, which signal can be of any suitable form and construction. As shown, the arm has secured thereto a battery F,

either a storage or other form of battery having sufficient power to work an electric light G, connected with the battery by a wire f, running from one pole of the battery to the 5 electric light, and a return-wire f' from the electric light, running to the arm in line with the sliding plate or cover in, the arrangement shown, and a return-wire f² from the arm to the other pole of the battery, so that when a 10 circuit is established through the wires f, f', and f² the electric light will be on to display the signal, which may be a red glass or other appliance g' in a reflector g, surrounding the electric light, or any other suitable form of 15 danger-signal may be employed. The arrangement shown has the connection between the battery and electric light completed with the withdrawing or receding of the plate or cover from in front of the signal, which will 20 occur when the bridge, trestle, or other structure is washed away or broken down, carrying with it the signal-operating means, which 25 pulls on the wire or other connection leading to the sliding plate or cover and draws such plate or cover back to open the signal. On 30 the inner face of one of the guides e of the arms, as shown, are two metal plates h and h', with a space h² between them, and the adjoining edge of the sliding plate or cover E' 35 has thereon a metal plate h³. The space h² is located so that when the sliding plate or cover is in its advanced position the plate h' will not be contacted by the plate h³ to complete the circuit from the battery; but with 40 the withdrawal of the plate or cover into the position shown in Fig. 6 the plates h and h' will be connected by the plate h³, completing the circuit from the battery through the electric light back to the battery, turning on the 45 electric light and displaying the signal.

It is to be understood that in place of a signal by an electric light a signal from any other source of light which can be ignited by the operation of the signal-operating means from 45 the carrying away or falling of the bridge, trestle, or other structure can be employed. The ordinary signaling drop-arm for day, with a light-signal for night, can be utilized by having the arrangement such as to display 50 the day-signal or the night-signal if the bridge, trestle, or other structure is washed away or broken down. It will thus be seen that a danger-signal will be displayed whenever the bridge, trestle, or other structure is washed 55 away or broken down, carrying with it the signal-operating means, as such means will actuate the danger-signal through the connection therefrom to the signal, and this display of the danger-signal must occur whenever 60 ever the bridge, trestle, or other structure is in a condition to be impassable from the washing away or breaking down thereof.

The washing away or falling down of a bridge, trestle, or other structure can be signalled or imparted to a station H at a distance 65 from either end of the bridge by means of a suitable signal located in the station. This

signal may be a bell operated by electricity or other suitable signal. A signal for a station is illustrated diametrically in Fig. 7 and 70 is an electric bell. The battery I may be the battery of the station connected with the telegraph or it may be an independent battery, and this battery has a conductor i, leading to one arm of a circuit-breaker J, which, as 75 shown, has two spring contact-arms j, separated by an insulation j', with a conductor i' leading from one of the arms to the bell and a conductor i² leading from the bell to the other pole of the battery, as is usual in connecting 80 electric bells with a battery. The two arms of the circuit-breaker J in the construction shown are held apart by an interposed wedge or block k', of insulating material, and this block is connected with a wire or other draw 85 connection k, running through a tube c² and attached to the main signal-operating means, and the tube c² may be the turned end of the tube c or it may be a branch tube leading therefrom to the station, so as to carry the 90 wire or other connection k into the station for operating the circuit. The withdrawal of the separating wedge or block k' by a backward pull or draw on the wire or connection k allows the arms of the circuit-breaker to contact, completing the circuit between the battery and bell and sounding the alarm. The withdrawal of the head or block will occur if the bridge, trestle, or other structure is washed 95 away or broken down, carrying with it the 100 main signal-operating means, as such means will remain with the bridge, trestle, or other structure and be washed away or carried down therewith, drawing on the wire or connection k and releasing the circuit-breaker to give the 105 alarm.

It will be understood that the alarm can be given both at the signal-post and at the station at the same time and from the same main operating means, or the post alone can be depended upon to give the signal where the station is too far removed, or if the station is sufficiently close the signal-post can be dispensed with and the alarm be given directly to the station, and in any event the operation 115 of the signal must occur with the washing away or breaking down of a bridge, trestle, or other structure, as the main operating means are permanently fixed thereto and go therewith, with the result of displaying a danger-signal observable from an approaching engine or train and warning those in charge of the engine or train that there is danger ahead. 120

It is preferred where the track-signal-operating means extend a considerable distance 125 beyond each end of the danger-point to a station or signal-post to inclose such means in a tube; but this is not an absolute necessity, as the track-signal-operating means could be run over the ties and held loosely by eyes or 130 staples, and the main purpose of the tube or casing is to prevent easy tampering with the track-signal-operating means, so as to display the danger-signal. The track-signal-operat-

ing means could be run direct into the signal-post or upright where it is not desired to operate a station-signal at some distance away, and the station-signal could be a hollow post or upright with a signal-arm, or a signal-arm or other signal could be employed at the station instead of the alarm-bell, it being immaterial in carrying out the invention as to how the signal is operated or what the nature of the signal may be so long as the track-operating signal is connected so as to perform its work in case of the washing away or falling of a bridge, trestle, or other structure.

In the claims the track-signal-operating means is called a "wire;" but it is understood that this term covers the use of a cord or other similar device.

What I regard as new, and desire to secure by Letters Patent, is—

1. In a railway-signal, the combination with a track-supporting structure, of a track-signal-operating wire permanently secured to the track-supporting structure, a post and an

arm on the post carrying an electric light and a slide automatically withdrawn to expose 25 the light by tension of the track-signal-operating wire produced by displacement of the rail-supporting structure and the track-signal-operating wire carried thereby, substantially as described.

2. In a railway-signal, the combination with a track-supporting structure, of a track-signal-operating wire permanently secured to the track-supporting structure, a post and an arm on the post carrying a light and a slide 35 automatically withdrawn to expose the light by direct tension of the track-signal-operating wire produced by displacement of the rail-supporting structure and the track-signal-operating wire carried thereby, substantially as described.

GENEROUS L. WILSON.
